UNITED STATES PATENT OFFICE.

WILLIAM A. SHAW, OF SHELBY, OHIO.

FENCE-POST.

SPECIFICATION forming part of Letters Patent No. 424,139, dated March 25, 1890.

Application filed September 23, 1889. Serial No. 324,837. (No model.)

To all whom it may concern:

Be it known that I, WILLIAM A. SHAW, of 5
Shelby, in the county of Richland and State
of Ohio, have invented a new and useful Im-
provement in Fence-Posts; and I do hereby
declare that the following is a full, true, and
exact description thereof.

The nature of my invention relates to a
hollow or tubular base with concave sides
10 and slats attached thereto, which form braces
for supporting the wire or board fence and
for adjusting the fence in its proper position,
as conditions may require.

That the invention aforesaid may be fully
15 seen and understood, reference will be had
to the following specification and the an-
nexed drawings, in which—

Figure 1 is a front elevational view of the
said post with sections of wire fence con-
20 nected therewith. Fig. 2 is a side view of
Fig. 1, showing the lower part in section.
Fig. 3 represents the said post with sections
of a board fence. Fig. 4 is a top view; and
Fig. 5, a cross-section of the base in direction
25 of line x , Fig. 3.

Like letters designate like parts in the
specification and drawings.

The base A is preferably made of cement
or burnt clay or material technically known
30 as "stoneware"—such as sewer-pipe or tiling—
to resist the destructive action of the weather
and earth to which it is subjected. Said
base consists of a hollow four-sided structure
35 with concaving sides, as shown in the draw-
ings. On two opposite sides are slats, which
constitute the support for and to which the
wire C or boards D are attached, as seen in
Figs. 1, 2, and 3. Said slats are preferably
40 made of wood, but may be of any other suit-
able material.

The brace E, Figs. 2 and 4, is attached to
the supporter B by means of a screw-bolt F
at the upper ends. The lower terminals
thereof are screw-bolted or otherwise fast-
45 ened on the opposite sides of the base A in
the respective concaves, as seen in Fig. 2.
The concave sides b of the base are shown in

Fig. 4, which concave, with the bolt-fastening
of the brace and support to the base, prevents
the longitudinal movement of the fence.

50

In case the fence from any cause is swayed
or turned in a lateral direction it may be
strengthened up without disturbing the post
or posts simply by withdrawing the screw-
bolt a, then raising or lowering the brace to 55
move supporter B up to a vertical position,
and by adjusting the supporter so that the
bolt-holes c will register with the holes in
the base for the passage of the screw-bolt to
receive the adjusted fence in its upright po- 60
sition. The same means essentially are ar-
ranged at the upper ends of the brace and
supporter, at which end the brace can be re-
enforced—that is, the supporter B straight-
ened by inserting the bolt F through the hole 65
d, as indicated in Fig. 1. The brace in that in-
stance is still more positive in its resistance
for holding the supporter B in an upright
position. The adjustment at the upper end
can be made without regard to that of the 70
lower end, or vice versa.

As seen in Fig. 2, the base A is provided
with lids e at each end or top and bottom, re-
spectively. Said lids are cemented or sealed
to the base A, to exclude rain and prevent 75
water from entering the interior of the base.
Thus the danger of cracking by reason of
the formation of ice is avoided. The form
of the base A also admits of using either end
thereof for connection with the slats. Thus, 80
if one end has become defective during the
drying or burning process, then the same is
used for insertion and the perfect one for at-
tachment of the slats. In every instance
provision is made that water is prevented 85
from entering or leaking through the bolt
holes or openings g.

In wire fences staples or hooks G are used,
as seen in Figs. 1 and 2, whereas when boards
are used then they are directly nailed upon 90
the supporter B, as seen in Fig. 3.

What I claim, and desire to secure by Let-
ters Patent, is—

In a fence-post, the combination of a hol-

low earthen base A, having concave sides, a supporter B, and a brace E, the lower end of said supporter and brace being in adjustable contact with opposite sides of said base by 5 means of a screw-bolt or its equivalent, and a series of registering holes to receive said bolt for adjustment, the upper ends of said supporter and brace held in adjustable contact with each other in like manner, con-

structed and arranged substantially as and to for the purpose described.

In testimony whereof I affix my signature in presence of two witnesses.

WILLIAM A. SHAW.
